UNITED STATES PATENT OFFICE.

CHARLES TWEEDIE, OF JEFFERSON, MISSOURI.

DESIGN FOR A SHOE-LACE.

No. 38,993.

Specification for Design.

Patented Jan. 7, 1908.

Application filed July 29, 1907. Serial No. 386,171. Term of patent 3½ years.

To all whom it may concern:

Be it known that I, CHARLES TWEEDIE, a citizen of the United States, and a resident of the city of Jefferson, county of Cole, and State of Missouri, have invented a new, original, and ornamental Design for a Shoe-Lace, of which the following is a specification.

My design consists in the features shown

in the accompanying drawing which forms part of this specification.

I claim:

The ornamental design for a shoe lace shown.

CHARLES TWEEDIE.

In the presence of—

W. C. HOEFER,

E. E. WARD.
